HOLD-DOWN SLEEVE FOR EXPANSIVE REAMERS

Filed March 7, 1930

Inventor.
John. Grant.

Attorney.

UNITED STATES PATENT OFFICE

JOHN GRANT, OF LOS ANGELES, CALIFORNIA

HOLD DOWN SLEEVE FOR EXPANSIVE REAMERS

Application filed March 7, 1930. Serial No. 434,020.

This invention has for its general object the provision of a device for holding in contracted position the expansive cutters of an expansive reamer or underreamer; and thereby to transform, in effect, such an expansive reamer or underreamer into a plain or non-expansive reamer.

Although the invention is not limited to any particular form of expansive reamer or underreamer, it will best be understood in its general characteristics, principal and scope from a consideration of specific application of an illustrative embodiment to a particular type of expansive underreamer. That selected type of expansive underreamer involves a tubular slotted body and an internal cutter abutment core or mandrel; the cutters being held in the body slots and riding up and down the internal mandrel for expansion and contraction. The internal mandrel is so formed that when the cutters move upwardly they move outwardly to expanded position. By holding the cutters down they can be prevented from moving outwardly in expansion; and the expansive underreamer is thus transformed into a non-expansive plain reamer having a reaming diameter equal to the contracted diameter of the expansive reamer.

The hold-down sleeve which is applied to this particular type of reamer also has provision for positively holding the cutters inwardly and for preventing their loose outward movement; and when held in their inner contracted positions, the structure is such that the cutters bear inwardly against the internal abutment mandrel and also bear inwardly against each other. The resulting structural arrangement is thus of great solidity and strength.

The invention in its various aspects will now be best understood from a detailed and specific description of the chosen illustrative embodiment, as applied to the particular type of expansive underreamer chosen as an illustration of the applicability of my invention. For this purpose reference is had to the accompanying drawings in which:

Figure 1 is a central longitudinal section

showing an underreamer of said type equipped with my present invention;

Fig. 2 is a similar section showing the same underreamer with the hold-down sleeve removed, and with the underreamer in expanded position; 55

Fig. 3 is an enlarged cross section on line 3—3 of Fig. 1;

Fig. 4 is an enlarged cross section on line 4—4 of Fig. 1; 60

Fig. 5 is a detail elevation of a modified form of hold-down sleeve.

In the drawings the tubular body of the underreamer is illustrated at 10 and the longitudinally extending body slots at 11. In 65 the particular underreamer illustrated there are three circumferentially equidistant body slots; but this number, which is equal to the number of the cutters employed, may be varied as desired. The cutters are here illustrated as comprising cutter carriers 12 having roller cutters 13; but it will be understood that any type of ultimate cutter or cutting edge may be used. Consequently, for the purpose of this explanation, the elements of each cutter, including the cutter carrier 12 will be hereinafter referred to as an entity, and merely as the cutter. 70

Within the tubular body is an internal cutter abutment and expanding mandrel 15 which, in the form here illustrated, has a relatively large upper part 16 which is of somewhat smaller diameter than the internal bore of the tubular body. Immediately below this upper larger part 16 is an abrupt diagonal expanding shoulder 17; then below that shoulder is a cylindric mandrel part 18; and below part 18 the mandrel has a downwardly tapered portion 19. Then a mandrel extension 20 extends on down through the tubular body, and the cutter expanding spring 21 is mounted in the lower part of the body around this mandrel extension 20; the lower end of the spring resting upon some suitable support which is stationary with reference to the mandrel. For instance, in this particular design, where the body is also stationary with reference to the mandrel, the lower end of the spring may rest upon the collar 22 which is secured in the body or 80

which is supported upon the upper end of the tool joint pin 23 of the drill bit 24 which is usually attached at the lower end of such an underreamer. The upper end of spring 21 presses upwardly against a cutter propeller plunger 24 which in turn presses upwardly on the lower ends of the cutters. By inspection of the drawings it will be seen that the inner mandrel contacting surfaces of the cutters are so formed that when the cutters are moved upwardly they are also moved outwardly by interaction with the mandrel. In such upward movement, in this particular type of underreamer, the extreme lower ends of the cutters are not moved outwardly; the extreme lower ends riding up the cylindric mandrel extension part 21, to the position shown in Figure 2. Thus when the cutters ride up to the position of Figure 2, their lower ends not only bear inwardly against tapered portion 19 of the mandrel but the cutter wings 12a may also bear inwardly and circumferentially against each other. Figure 4 shows this circumferential bearing of the cutter wings when the cutters are contracted; and the same condition is true of the lower ends of the cutter wings when expanded as shown in Figure 2. The lower ends of the cutter wings as clearly shown in Figure 4 are of sufficient thickness (radial dimension) to fill the space between the mandrel part 20 and the wall of the tubular body; so that the lower ends of the cutters not only bear inwardly against the mandrel, but also inwardly, circumferentially, against each other and also outwardly against the tubular wall of the body.

Also, in the contracted position of Figure 1, the upper ends of the cutter wings bear inwardly, circumferentially, against each other, as is shown in Figure 3. In this lower and contracted position of the cutters, their upper ends also bear inwardly against the part 18 of the cutter abutment mandrel, as shown in Figure 3. But, in this contracted position, the upper parts of the wings do not bear outwardly against the body wall as they must be spaced inwardly from the body wall far enough to allow for the outward expansive movements of the cutters when they move out to the position of Figure 2 where the upper ends of the cutter wings do bear outwardly against the body wall. Thus, in the contracted cutter positions the disposition of the cutter wings 12a at their upper ends, is such as is clearly shown in Figure 3 bearing circumferentially against each other and inwardly against the abutment mandrel.

There is, as I have said, an annular space between the upper large mandrel portion 16 and the body wall; and it is into this annular space that the upper ends of the cutter wings move upwardly when the tool is expanded. To hold the cutters down and thus to keep them from expanding, I insert into this an-

nular space a sleeve 30 of such length that its upper end may bear upwardly against the downwardly facing shoulder 31 on the mandrel, and that its lower end bears downwardly against the upper ends of the cutters. If the cutters merely were to be held down, then the lower end of this hold-down sleeve could be plain and straight; but, in holding the cutters down in contracted position, it is also desirable to hold them against any loose movement, both laterally and outwardly. Thus I provide the lower end of the hold-down sleeve 30 with three equidistantly spaced and downwardly extending lugs 32 which are of such size and shape as to enter into and fill the spaces between adjacent cutters and between the cutter wings and the body wall. This may be seen most clearly by inspection of Figures 1 and 3. These downwardly extending lugs thus fill the inter-cutter spaces within the body, and prevent the cutters from having any loose motion laterally, and also positively prevent them from moving loosely outwardly, while they are held down in their contracted positions.

The upper ends of the cutters bear upwardly in what may be called the notches 33 between adjacent lugs 32. The upper ends of the cutters, where they engage upwardly against the sleeve 30, are square, as indicated at 40; although the upper inner corners are diagonal, as at 41, to co-operate with the diagonal expanding face 17 of the mandrel. The lower end surfaces of the sleeve (the surfaces which form the upper edges of notches 33) are also square. Spring 21 presses the cutters up with considerable force; so that the cutters are clamped longitudinally between the cutter propeller 24 at their lower ends and the sleeve 30 at their upper ends. This clamping may be in many cases sufficient to hold the cutters inwardly and thus lugs 32 might be dispensed with; but in the actual practice of reaming the cutters may at times be subjected to tangential forces tending to work them outwardly, and the rise of lugs 32 positively prevents this.

Thus, by using the hold-down sleeve 30, the cutters of the underreamer are held down and prevented from being forcibly expanded, and at least are frictionally clamped against outward movement; and using the hold-down sleeve having the described notched lower end, the cutters are additionally held positively and rigidly against outward expansive movement; and the whole structure is made solid and rigid in its contracted position. Thus, the normally expansive underreamer is transformed easily into a plain non-expansive reamer of great rigidity and strength.

In order to make the tool again an expansive reamer, it is only necessary to remove the hold-down sleeve 30, and that, in this particular case, may easily be done by removing the internal mandrel, which, in this

particular design, is screw-threaded at 34 at its upper end into the upper end of the body. When the hold-down sleeve 30 is removed, I usually provide another shorter sleeve 50 which moves down when the cutters move down and which performs the function of closing the otherwise open upper ends of the cutter slots 11 and preventing entry of mud and other matter which might clog the reamer. This protective sleeve is, however, 10 not the particular subject-matter of this present application, but rather the subject-matter of my application Serial No. 260,713, filed March 10, 1928, allowed January 30, 1930, and now Patent No. 1,773,307. It is possible, however, to utilize this shorter protection sleeve 50 as a part of the longer hold-down sleeve. For instance, by simply providing a 15 shorter sleeve 30a, such as shown in Figure 5, formed at its lower end with the notches 33 and the extension lugs 32, and making the additive lengths of sleeve 50 and sleeve 30a equal to the total length of sleeve 30, the two sleeves 30a and 50 may be used together. It 20 will be readily apparent how the internal mandrel may be removed upwardly from the body, and sleeve 30a slipped upwardly on the mandrel to a position immediately below sleeve 50, and then the whole assembly put 25 back into the underreamer body. Then the two part sleeve 30a, 50 will act exactly as does the single integral sleeve 30.

It will be understood, as I have indicated, 30 that the particular reamer design here set out is no limitation on my invention, but that the sleeve may be used in other specific reamer designs. For instance, while I have described the mandrel and body as separate pieces they 35 need not be. Also, although I have described the body as fixed relative to the expanding mandrel, that specific fact is not a necessary limitation on the invention, and so neither 40 is the form of the body or mandrel. The function of the mandrel, in so far as my present invention is concerned, is to cause lateral 45 expansion of the cutters on relative longitudinal movement in one direction. The function of the body, as here described, in so far as it has to do with my present invention, is 50 merely to hold the cutters in around the mandrel; and it is immaterial to this function whether the body moves longitudinally with the cutters or remains stationary with the mandrel.

55 I claim:

1. In combination with an expansive reamer which embodies an internal cutter expanding mandrel, cutters surrounding the mandrel and movable longitudinally thereon, and a body confining the cutters about the mandrel, the mandrel and cutters being so formed that relative longitudinal movement between them in one direction causes outward expansive movement of the cutters; a removable sleeve fitting around the

mandrel and bearing against the cutters longitudinally to prevent longitudinal expansive movement.

2. In combination with an expansive reamer which embodies an internal cutter expanding mandrel, cutters surrounding the mandrel and movable longitudinally thereon, and a body confining the cutters about the mandrel, the mandrel and cutters being so formed that relative longitudinal movement between them in one direction causes outward expansive movement of the cutters; a removable sleeve bearing longitudinally against a shoulder provided on the mandrel, and bearing longitudinally against the cutters to prevent longitudinal movement of expansion.

3. In combination with an expansive reamer which embodies an internal cutter expanding mandrel, cutters surrounding the mandrel and movable longitudinally thereon, and a body confining the cutters about the mandrel, the mandrel and cutters being so formed that relative longitudinal movement between them in one direction causes outward expansive movement of the cutters; a removable sleeve fitting around the mandrel and bearing against the cutters longitudinally to prevent longitudinal expansive movement, said sleeve having a circumferentially spaced extensions which enter between adjacent cutters and between the cutters and the surrounding body, to hold the cutters rigidly.

4. In combination with an expansive reamer which embodies an internal cutter expanding mandrel, cutters surrounding the mandrel and movable longitudinally thereon, and a body confining the cutters about the mandrel, the mandrel and cutters being so formed that relative longitudinal movement between them in one direction causes outward expansive movement of the cutters; a removable sleeve bearing longitudinally against a shoulder provided on the mandrel, and bearing longitudinally against the cutters to prevent longitudinal movement of expansion, said sleeve having circumferentially spaced extensions which enter between adjacent cutters and between the cutters and the surrounding body, to hold the cutters rigidly.

5. In an expansive reamer, the combination of an internal longitudinal cutter expanding mandrel having a relatively large cutter expanding part near one end and a relatively small part nearer the other end; a cutter holding body annularly spaced around the mandrel so as to leave an annular space between the body and the larger part of the mandrel, cutters mounted in the body around the mandrel and longitudinally movable on the mandrel and adapted to ride longitudinally onto the larger mandrel parts and to be expanded thereby, laterally ex-

- tending wings on the cutters which, in the contracted position of the cutters bear circumferentially against each other, and a removable sleeve fitting into and filling the annular space between the larger part of the mandrel and the surrounding body to prevent longitudinal movement of the cutters onto the larger part of the mandrel.
6. In an expansive reamer, the combination of an internal longitudinal cutter expanding mandrel having a relatively large cutter expanding part near one end and a relatively small part nearer the other end; a cutter holding body annularly spaced around the mandrel so as to leave an annular space between the body and the larger part of the mandrel, cutters mounted in the body around the mandrel and longitudinally movable on the mandrel and adapted to ride longitudinally onto the larger mandrel parts and to be expanded thereby, laterally extending wings on the cutters which, in the expanded position of the cutters enter into the annular space between the mandrel and body, and a removable sleeve fitting into and filling the annular space between the larger part of the mandrel and the surrounding body to prevent longitudinal movement of the cutters onto the larger part of the mandrel.
7. In an expansive reamer, the combination of an internal longitudinally cutter expanding mandrel having a relatively large cutter expanding part near one end and a relatively small part nearer the other end; a cutter holding body annularly spaced around said mandrel so as to leave an annular space between the body and the larger part of the mandrel, cutters mounted in the body around the mandrel and longitudinally movable on the mandrel and adapted to ride longitudinally onto the larger mandrel parts and to be expanded thereby, laterally extending wings on the cutters which, in the contracted position of the cutters bear circumferentially against each other and, at one end of the wings, bear outwardly against the body, and a removable sleeve fitting into and filling the annular space between the larger part of the mandrel and the surrounding body to prevent longitudinal movement of the cutters onto the larger part of the mandrel, said sleeve having circumferentially spaced longitudinal extensions which enter into spaces between adjacent cutters and between the cutter wings and the surrounding body.

In witness that I claim the foregoing I have hereunto subscribed my name this 31 day of January, 1930.

JOHN GRANT.
